PHONOGRAPH RECORD RESURFACING
MACHINEGeorge H. Fritzinger, Orange, N. J., assignor to
Thomas A. Edison, Incorporated, West Orange,
N. J., a corporation of New Jersey

Application December 17, 1938, Serial No. 246,304

29 Claims. (Cl. 82—1.1)

This invention relates to machines for resurfacing phonograph records. Although no unnecessary limitation thereto is intended, the invention has particular utility, and is illustrated and described, in connection with such machines as are adapted for resurfacing phonograph records of the type commonly used with commercial phonographs, or dictating machines. In some respects this invention has certain features in common with those disclosed in the copending applications of Richard M. Somers, Serial Nos. 232,766 and 264,774 respectively filed October 1, 1938 and March 29, 1939, and respectively entitled "Phonograph record shaving machines" and "Phonograph record resurfacing machines," which applications are connected by common ownership with the present application.

Phonograph record resurfacing machines of the above mentioned type commonly comprise a mandrel for supporting a record for rotation, and a resurfacing tool mounted on a carriage which is moved across the record by a feeding means driven coordinately with the rotation of the mandrel. The resurfacing tool is movable into operative position relative to the record to cause, as the record is rotated and the tool is moved steadily thereacross, a resurfacing, or a cutting away of a surface layer, of the record for the purpose of removing recordations therefrom to permit a re-use of the record.

In the usual operation of a record resurfacing machine there is first taken a heavy cut from the record to remove substantially all of the record material necessary for the resurfacing of the record. There may then be taken a light or finishing cut to remove any unevenness on the record surface which may have resulted from the first cut, the finishing cut serving thus to leave the record surface in a highly smooth and polished condition.

It is an object of my invention to provide a well-nigh fool-proof machine for resurfacing phonograph records.

It is another object of my invention to provide a novel and improved form of phonograph record resurfacing machine adapted for taking both heavy and finishing cuts. A feature of my invention is to complete the resurfacing of a record by one reciprocation of the tool thereacross; this is done by causing the resurfacing tool to take heavy and finishing cuts as the tool is respectively advanced and returned across the record, from and to a start position.

It is another object of my invention to provide a machine of the type just described which is

largely automatically controlled, and which is yet so arranged as to enable the operator to exercise a high degree of control thereover, particularly in ways to permit the taking of heavy and finishing cuts at will by performing simple manipulations on the machine.

It is another object of my invention to automatically perform various operations on the machine incidental to its starting and stopping to facilitate the use of the machine, the performance of these operations being, however, so restricted as to prevent possible mis-operation of the machine.

It is another object of my invention to automatically control the machine in ways to permit immediate inspection of the record surface after each traversal of the tool thereacross.

It is a further object of my invention to cause a finishing cut to be made on the record by performing a single manipulation on the machine after a heavy cut has been taken.

In conventional phonograph record resurfacing machines it has been common to provide a tool-carriage which is both slidably and tiltably mounted, the carriage being tiltable so that the tool may be moved free of the record, without releasing the tool from a set position, and so that the carriage may be disconnected from its driving means to permit manipulation of the carriage across the record as desired. The carriage-driving means is commonly in the form of a feed screw with which there is engaged a feed nut carried by the carriage, the feed nut moving out of engagement with the feed screw when the carriage is tilted. With the above arrangement, the operator may accidentally attempt to manipulate the carriage while failing to tilt the same sufficiently to cause the feed nut to be fully disengaged from the feed screw, thereby causing the feed nut to scrape along the feed screw; the operator may also fail to release the tool from a previously set position, after mounting a thicker record on the machine than the previously mounted one, and then manipulate the carriage across the record, thereby causing possible damage to the record and tool by the scraping of the tool thereon.

It is an object of my invention to provide such improved arrangement of a machine as will cause such mis-operations as noted above, as well as other possible mis-operations, to be prevented. Various objects and features of my invention are to lock the carriage against manipulations across the record while the tool is in a set or operative position, to manually couple the driving means

with the carriage at will without tilting the latter, and to control the coupling of the carriage with its driving means by the tool-setting mechanism and/or at least in part as an incident of controlling the driving means.

It is another object of my invention to provide a new and improved form of finishing-cut controlling means.

It is another object of my invention to provide an improved form of tool-setting gauge for permitting the setting of the tool into operative position while the tool is off the record.

It is another object of my invention to retract or free the gauge from the record as an incident of setting the tool into operative position. A feature of my invention is to effect by a single manipulation, in the sequence here named, the setting of the tool into operative position, the locking of the same therein, and the retracting or freeing of the gauge from the record.

Another object of my invention is to cause the gauge to be moved relative to the tool, after the latter has been set into operative position, to retract the gauge from the record, and to automatically restore the gauge to render the same effective for a resetting of the tool as an incident of such resetting.

Another object is to restore the gauge into normal operative position relative to the tool as an incident of moving the tool out of operative position.

Other objects and features of my invention will appear from the following description and the appended claims.

35. In the description of my invention reference is had to the accompanying figures, of which:

Figure 1 is a top plan view of a phonograph record resurfacing machine in which my invention is incorporated, showing the tool-setting mechanism in operative position and the finishing-cut controlling means in inoperative position;

Fig. 2 is a top plan view of parts of the machine in accordance with my invention, principally showing in detail the interlinkage system largely dottedly shown in Fig. 1;

Fig. 3 is a vertical cross-sectional view of a portion of the machine in accordance with my invention, taken substantially along the line 3-3 of Fig. 1 but showing the finishing-cut controlling means in operative position;

Fig. 4 is a vertical cross-sectional view taken substantially along the line 4-4 of Fig. 1 but showing the tool-carriage in the vicinity of its start position;

Fig. 5 is an enlarged vertical cross-sectional view, taken substantially along the lines 5-5 of Fig. 1, principally showing an eccentric, journalled end portion of the carriage support rod;

60. Fig. 6 is a vertical cross-sectional view taken substantially along the line 6-6 of Fig. 1;

Fig. 7 is a fractional cross-sectional view of the tool-setting mechanism, showing the means for locking the tool in a set position;

65. Fig. 8 is a partial right hand view of the machine, generally similar to Fig. 6, but showing the tool-setting mechanism in inoperative position;

Fig. 9 is a vertical cross-sectional view taken substantially along the line 9-9 of Fig. 1, principally showing the operative connection between the carriage-driving means and the tool-setting mechanism;

Fig. 10 is a cross-sectional view taken substantially along the line 10-10 of Fig. 8;

Fig. 11 is a cross-sectional view, taken substantially along the line 11 of Fig. 10;

Fig. 12 is a cross-sectional view taken substantially along the line 12 of Fig. 10;

Fig. 13 is a view taken of a portion of the tool-setting mechanism showing a modified form of tool-setting gauge;

Fig. 14 is a cross-sectional view taken substantially along the line 14-14 of Fig. 13; and

Fig. 15 is a cross-sectional view taken substantially along the line 15-15 of Fig. 13, and showing in dash-dot lines the retracted position of the gauge while the tool is in set position.

Reference being had to the figures, particularly Figs. 1 and 6, there will be seen a phonograph record resurfacing machine in which my invention is incorporated. The machine comprises a base plate 1 provided with various up-right standards; a left-hand standard 2, an intermediate standard 3, another intermediate standard 4 positioned in front of the standard 3, right-hand standards 5, 6 and 7 respectively positioned from back to front, and other standards hereinafter mentioned. In the right-hand portion of the base plate 1 adjacent to the standard 6 there is also provided an upright boss 8 on which there is pivotally mounted, by a screw 9, an end-gate 10 normally held in closed position (as shown in Fig. 1) by a latch 11 pivoted to a rightward extension 7' on the standard 1. 30 The end gate 10 supports a conically pointed stud 12 adjustable with respect thereto as by an adjusting screw 13; the standard 2 supports another conically pointed stud 14 secured thereto by a set screw 15. The studs 14 and 12 form 35 left and right thrust bearings for a shaft 16 which passes through an oversized hole 17 in the intermediate standard 3 and which carries a mandrel 18 for holding a cylindrical record 19 to be resurfaced. In the operation of mounting 40 a record on, or removing a record from, the mandrel 18 the end-gate 10 is swung open to expose the right end of the mandrel. During the time the end-gate is open the shaft 16 is 45 intermediately supported by the standard 3 and retained in engagement with the stud 14 by means of a collar 20, secured to the shaft by a screw 21, which abuts against the intermediate standard 3 to limit movement of the shaft in a 50 rightward direction.

Respectively supported by the front left and right standards 4 and 7 and by the left and right standards 2 and 6 are the front and back rods 22 and 23 extending laterally along the mandrel 18. When the end-gate 10 is closed 55 the mandrel 18 is rotatably supported in parallel relation to each of the rods 22 and 23. Slidably mounted on the rods 22 and 23 is a tool-carriage 24 having a sleeve bearing 25 embracing the rod 23. As shown in Fig. 6, the carriage 60 24 is substantially semi-circular in shape, curving forwardly from the back rod over the mandrel 18 and terminating in an open slot 26 in which slidably fits the front rod 22. The carriage is thus mounted for movement back and 65 forth across, and throughout the length of, the mandrel 18.

On the right side of the carriage there is an extension 27, square-shaped as viewed from the side thereof, which substantially overlies the rod 23. This extension carries a resurfacing tool 28 comprising a knife blade 29 mounted on a knife bar 30 which is slidably supported by the extension 27 for movement towards and away from the record, the knife bar being restricted 75

against turning by a key 100 engaging a longitudinal slot 100' provided in the bar. The means for setting the resurfacing tool into operative position—a position of the tool in which the knife blade 29 engages the record—and for releasing the same from operative position may be of a construction such, for example, as is disclosed in Brown Patent No. 2,137,383, issued on November 22, 1938, and entitled "Record shaving machine."

The tool setting and releasing mechanism of the type above mentioned is shown in Figs. 1, 6 and 8, and may be briefly described as follows: A cap 31 is slidably mounted on the extension 27 and secured by a screw 32 to a guide rod 33 slidably supported by the extension 27 in parallel relation to the knife bar 30. The cap 31 is resiliently coupled to the knife bar in order that when the cap is moved downwardly towards the record the knife bar is yieldably moved therewith. This resilient coupling comprises a compression spring 34 coiled about a reduced-diameter portion 30' of the knife bar 30 between a shoulder 30'', formed by the reduced diameter portion 30', and the top of the cap 31. The cap 31 is urged upwardly by a compression spring 35 coiled about guide rod 33 between the extension 27 and the top of the cap 31, but upward movement of the cap 31 relative to the knife bar 30 is limited by the contact of the top of the cap 31 with a headed screw 36 on the bar. By reason of the upward biasing of the cap 31, the resurfacing tool 28 is normally maintained in inoperative position, this position being defined by the contact of a stop collar 37, secured to the knife bar in a manner hereinafter explained, with the underside 31' of the carriage extension 27.

The setting of the tool into operative position, and its release therefrom, is controlled by a lever 38 pivoted on the right side of the carriage extension 27, as on a post 39, and having a short arm 40 which is coupled to the cap 31 by an angular link 41, the link being pivoted to the arm 40 by a pin 42 and to the cap 31 by the pivot screw 43. As the lever 38 is swung forwardly in a counter-clockwise direction the cap 31 and the knife bar 30 are moved towards the record to effect the setting of the tool into operative position. Such forward or setting movement of the lever 38 is limited to the position shown in Fig. 6 by the impingement of the link 41 against the hub 38' of the lever. When the lever 38 is in this most forward position the pin 42 is slightly past dead center with respect to the pivot axes of the lever 38 and the pivot screw 43; the upward biasing force exerted on the cap 31 then causes the lever 38 to be urged in a counter-clockwise direction. Thus when the lever 38 is moved in a counter-clockwise direction into its most forward position wherein the hub 38' contacts the link 41, the lever is releasably held in that position to maintain the tool 25 in operative position; and when a slight "tripping" movement is imparted to the lever 38 in a clockwise direction to return the pin 42 across the dead center line aforementioned, the tool will be released from operative position by reason of the upward biasing of the cap 31.

In performing a resurfacing operation the resurfacing tool is first set into operative position relative to the record to be resurfaced, and then the tool is made to traverse the record longitudinally thereof coincidentally with a rotation of the record. As the tool so traverses the record a surface layer of the record is cut away,

this cut-away layer being directed downwardly by a chip chute 44, secured to the knife bar by a screw 44', through a laterally extending opening 45 in the base plate 1, for example into a suitable container not shown.

A traversing movement of the tool relative to the record is caused by feeding the carriage 24 along its support rods 22 and 23. The feeding means for the carriage comprises a feed screw 59 rotatably supported by the left and right standards 2 and 5 respectively carrying conically pointed studs 60 and 61 which serve as thrust bearings for the feed screw. On the left side of the carriage 24 there is provided a block 62 (see Fig. 9) embracing the carriage sleeve 25 but held against movement longitudinally of the sleeve by a stop collar 63 secured to the sleeve by a set screw 63'. Secured to the block 62 by the screws 62' is a resilient and rearwardly extending arm 64 carrying a feed nut 65 which normally engages the underside of the feed screw 59. When the feed nut and feed screw are engaged, a rotation of the feed screw will cause a steady movement of the carriage along the record, the direction of carriage movement depending upon the direction of rotation of the feed screw.

The feed screw is adapted to be rotated in one direction or the other, as desired, coincidentally with a rotation of the mandrel shaft 16 by a mechanism comprising a beveled gear 66 rotatably mounted on a shaft portion 59' of the feed screw 59 and coupled by an intermediate beveled gear 67, journaled in a standard 68, to another beveled gear 69 generally similar to the gear 66 but carried by a pulley 70 also rotatably mounted on the shaft portion 59'. On the shaft portion 59' there are provided left and right stop collars 71 and 72 which serve to hold the gears 69 and 66 in engagement with the intermediate gear 67. With this arrangement a rotation of the pulley 70 will cause the gear 66 to be rotated at the same rate as that of the pulley but in a direction opposite thereto. The gears 66 and 69 are each freely rotatable on the shaft portion 59' but may be selectively connected with the feed screw 59 to cause the feed screw to be turned in either one direction or the other.

The connection of the gears 66 and 69 with the feed screw 59 is effected by a clutch mechanism comprising toothed clutch members 73 and 74 embracing the shaft portion 59' and respectively secured to the gears 66 and 69 on their adjacent sides. On the shaft portion 59' between the clutch members 73 and 74 there is provided a sliding clutch collar 75 suitably splined to the shaft portion 59' as by a screw and slot arrangement of which the screw appears as 76. The clutch collar 75 is provided at its left and right sides with teeth adapted for selective engagement with the toothed clutch members 74 and 73. When the clutch collar 75 is moved to the left into engagement with the clutch member 74, the feed screw 59 is connected with the pulley 70 for rotation therewith. When the clutch collar 75 is moved to the right into engagement with the clutch member 73, however, the feed screw is connected with the gear 66; since the gear 66 is rotatably coupled to the pulley 70 for rotation in the direction opposite thereto the feed screw will now be rotated in the direction opposite to that of the pulley 70.

When the machine is in use the pulley 70 is rotated continuously, in a clockwise direction as viewed from the left end thereof, as by a belt 75

(not shown) coupling the pulley 70 with a drive pulley 77 on the mandrel shaft 16. The direction of the threads on the feed screw 59 is such that a clockwise rotation of the feed screw, as viewed from the left end thereof, will cause a leftward movement—hereinafter called the advance movement—of the carriage 24. Thus when the clutch collar 75 is in engagement with the clutch member 74 the carriage-feeding means is conditioned for carriage advance, and when the clutch collar is in engagement with the clutch member 73 the carriage-feeding means is conditioned for carriage return.

The driving of the carriage-feeding means, as well as of the rotation of the record 19, may be effected by a suitable driving motor, not herein necessary to show, which may be located beneath the base plate 1 and be coupled to a pulley 78 on the mandrel shaft 16 as by a belt (not shown) which may pass through an opening 79 in the base plate 1. The starting and stopping of the driving action of the motor may be controlled at will by a suitable toggle switch 80 adapted to snap into "on" and "off" positions and having a pair of terminals 81 connected to a pair of leads 82 by which the switch may, for example, be serially connected in the power supply circuit (not shown) of the motor. The switch 80 is located beneath the base plate 1 in the right forward section thereof and is supported by the base plate 1 as by left and right brackets of which the right bracket appears as 83, this bracket being secured to the switch by the screws 84 and to the base plate by the screw 84'. Extending forwardly from the switch is an operating lever 85 rockable to the right and left to throw the switch to "on" and "off" positions. The means for manually moving the switch 80 into its respective positions comprises a forwardly extending control lever 86 having a vertical shaft portion 86' pivoted in a boss 87 extending downwardly from the base plate 1. Located beneath the boss 87 and secured by a screw 88 to the shaft portion 86' is a plate 89 having variously extending portions as herein-after described (see Fig. 2), one of these portions being in the form of a rearwardly extending arm 90. Pivoted to the arm 90 is a vertical post 91 having a vertical slot 92 through which slidably passes the switch lever 85. Thus left and right rocking movements of the control lever 86 will cause the switch 80 to be thrown into its "on" and "off" positions, indicated in Fig. 2.

Consideration being given to the structure as described so far, it will be seen that the carriage 24 is mounted so that, unlike conventional machines, it is not tiltable to disengage the feed nut 65 from the feed screw 59. In accordance with my invention this type of carriage mounting is employed to force the operator to release the resurfacing tool from a set position before manipulating the carriage across the record, thereby avoiding possible damage to the resurfacing tool and record as by a scraping of the tool thereon. Such forced release of the tool to permit a manipulation of the carriage is effected by causing the tool-setting mechanism to control the engagement of the feed nut with the feed screw, this control being such that the feed nut and feed screw are in engagement when the tool is set in operative position and out of engagement when the tool is out of operative position.

The means for so controlling the engagement of the feed nut with the feed screw is shown in Figs. 1, 6 and 9 and comprises a bar 93 secured to the left side of the cap 31 by the screws 94 and carry-

ing a pair of spaced leftwardly extending pins 95. Integrally formed with the feed nut carrying arm 64 is a resilient upstanding arm 96 which terminates at a point between the pair of pins 95. When the resurfacing tool 28 is set into operative position, the cap 31 then being moved downwardly, the upper one of the pins 95 contacts the arm 96 and causes the block 62 to be rocked on the carriage sleeve 25 in a clockwise direction (as it appears in Fig. 9), thereby effecting the engagement of the feed nut 65 with the feed screw 59; when the resurfacing tool 28 is released from operative position, the cap 31 then being moved upwardly, the lower one of the pins 95 contacts the arm 96 and causes the block 62 to be rocked in a counterclockwise direction, thereby effecting the disengagement of the feed nut from the feed screw. Thus the lever 38 which serves as a manual means for setting and releasing the tool, also serves as a manual means for moving the feed nut into and out of engagement with the feed screw.

In taking a first or heavy cut from the record the tool is set into operative position and the carriage is then advanced—i. e., moved leftwardly—across the record from its most rightward position wherein the tool is to the right of the record, this position of the carriage being called its start or first terminal position. Since the carriage is locked against manipulation, by the engagement of the feed nut 65 with the feed screw 59, whenever the tool is set in operative position, the operator is forced to set the tool while the carriage is in start position. To permit such setting of the tool there is provided a tool-setting gauge 97, which is offset to the left of the tool. When the resurfacing tool is set into operative position the tool and gauge are each moved towards the record until the gauge contacts the surface thereof, thereby positioning the tool relative to the record. Since the gauge is to the left of the tool—i. e., in the direction of tool advance in the taking of a heavy cut—it is important that the gauge be retracted from the record after the tool has been set. In accordance with my invention the retraction of the gauge from the record occurs automatically after the tool has reached a set or operative position, as an incident of tool setting. This is done by performing but a single manipulation on the machine: the moving of the tool setting lever 28 from its unoperated position shown in Fig. 8 to its operated or set position shown in Fig. 6. As the lever 38 is so moved, the tool is moved into operative position, locked in that position, and then the gauge is retracted from the record, in the sequence here named.

In the description of the tool-locking means and the tool-setting gauge 97—the other parts of the tool-setting mechanism having been heretofore described—reference is had to Figs. 6, 7, 8, 10, 11 and 12. The tool-locking means comprises a small pin 98 slidably mounted in the extension 27 for transverse movement with respect to the direction of movement of the knife bar 30. The inner end of the pin 98 slidably contacts a flat 99 provided on the knife bar 30 longitudinally thereof, whereas the outer end projects slightly beyond the right side wall of the extension 27. Pivoted on the post 39 between the lever 38 and the right side wall of the extension 27 is a cam member 101 in the form of a disc having an open sector 102 of substantially 90° in angular length. The cam member slidably engages the outer end of the pin 98, the portion of the cam member which so engages the pin being beveled to form a cam face 75

103 (see Figs. 7 and 10). The cam face 103 is of such shape that when the cam member is turned slightly in a counterclockwise direction, as it appears in Fig. 7, the pin 98 is pressed inwardly 5 against the flat 99 of the knife bar, thereby locking the bar. Such turning of the cam member 101 is adapted to occur as an incident of tool-setting by means of a coupling between the tool-setting lever 38 and the cam member 101 comprising a leftwardly extending pin 104 provided in the hub 38' of the tool setting lever and extending into the open sector 102.

As the lever 38 is swung forwardly to set the tool, the pin 104 first traverses the length of the open sector 102 and then, as the lever 38 is moved through the end portion of its travel, the pin 104 contacts the edge 102' of the sector and moves the cam member 101 therewith in a counterclockwise direction, causing the locking 10 of the resurfacing tool in its set position. When the lever 38 is released, the cap 31 is moved upwardly with considerable acceleration by the spring 35, thereby imparting a like acceleration 15 to the lever 38. The cap 31 is, however, momentarily stopped in its upward travel by its contact with the head 36 of the knife bar 30. While the cap 31 is stopped the inertia of the lever 38 causes it to move onwardly into its unoperated position, this onward movement of the 20 lever 38 being permitted by reason of the elongated slot 43' in the link 41 serving to form a loose connection between the link 41 and the cap 31. The movement of the lever 38 towards unoperated position causes the pin 104 to traverse 25 the length of the sector 102; as the lever 38 nears its unoperated position the pin 104 encounters the edge 102'' of the sector and moves the cam member 101 in a clockwise direction to cause the unlocking of the tool from its set position. 30 Immediately upon the unlocking of the tool the cap is moved further upwardly by the spring 35 to cause the tool to be moved into its inoperative position.

The tool-setting gauge 97 is carried by the 35 knife bar 30 but is adapted to have a controlled movement longitudinally of the bar. The gauge has a foot 105 adapted to contact the record surface during the setting of the tool and a collar portion 106 embracing the knife bar. The collar portion 106 is disposed between the stop collar 37 and the chip chute 44, the chip chute having a recess 107 surrounding the bar to permit an elongation of the collar portion 106 so as to provide a good bearing for the gauge 97 on the bar 30. Turning of the gauge relative to the 40 knife bar is prevented by a pin 108 in the chip chute engaging a slot 109 extending axially along the collar portion. On the side of the collar portion 106 adjacent to the stop collar 37 there are provided two shoes 110 angularly spaced on the collar portion by 180°. These shoes are urged 45 into contact with the stop collar 37 by means of a pair of compression springs 111 respectively disposed in a pair of recesses 112 provided in the body of the chip chute 44. These recesses are angularly spaced at 180° from each other and at substantially 90° from the shoes 110, and are open on the side of the chip chute which is adjacent to the collar portion 106.

50 While the resurfacing tool is being set and locked in operative position the gauge 97 is maintained in a fixed or normal position relative to the tool such that when the gauge is in contact with the surface of the record the tool is positioned relatively thereto to take a heavy or first

cut from the record, this position of the tool being called its set or operative position. Immediately after the tool is locked in its set position the gauge is retracted from the record by the terminal movement of the tool-setting lever 5 38. To effect this retraction of the gauge the stop collar 37 is pivoted on the knife bar 30, but is prevented from moving longitudinally of the bar, by means of a set screw 113 which threads radially through the collar and engages an annular groove segment 114 on the knife bar. The stop collar is also provided with a pair of inclined cam faces 115 angularly spaced at 180°. These cam faces are inset in the surface of the stop collar adjacent to the collar portion 106 15 and are adapted for respective engagement with the shoes 110. During the setting of the tool the shoes 110 are out of engagement with the inset cam faces 115. When, however, in the setting of the tool, the tool-locking means is rendered sufficiently effective to hold the tool in set position against the force of the spring 34 (which spring urges the tool towards the record by reason of it having been compressed during the operation of setting the tool), then the stop collar 37 is 20 turned by the terminal movement of the tool-setting lever 38. This turning of the collar 37 is effected by the contact of an arm 116 on the hub 38' of the lever 38 with a radially extending pin 117 on the collar 37, and is sufficient to cause 25 the inset cam faces 115 to move into line with the shoes 110. As this alignment occurs the gauge 97 is moved upwardly along the knife bar 30 by the compression springs 111 to cause the retraction 30 of the gauge from the record. 35

When the gauge has been moved upwardly along the tool, for retraction from the record, it no longer bears a normal position relative to the tool, and must therefore be restored to such a normal position when the tool is to be reset in 40 order that it may again perform its normal function. It is a feature of my invention to automatically cause such restoration of the gauge as an incident of releasing the tool from set position. To effect this restoration there is provided 45 on the hub 38' of the lever 38 an arm 118, angularly spaced at approximately 90° from the arm 116, which contacts the pin 117 as the lever 38 is moved into its unoperated position and thereby turns the collar 37 to cause the cam 50 faces 115 to be moved out of alignment with the shoes 110. As the cam faces 115 are so moved the gauge 97 is moved downwardly along the knife bar 30, against the force of the compression springs 111, into normal position relative to 55 the tool.

It is a feature of my invention that when the carriage is in start position the carriage feeding means is operable to effect only an advance movement of the carriage. This is done by a 60 means, hereinafter described, which automatically insures the engagement of the clutch collar 75 with the clutch member 74 whenever the carriage is in its start or first terminal position. Upon setting the tool into operative position while 65 the carriage is in start position, the operator need then only move the manual control 86 leftwardly into "on" position to place the machine in operation for the taking of a first or heavy cut. When the resurfacing tool has traversed the 70 record, the carriage reaching its leftward or second terminal position, it is desirable that the operator be permitted to immediately inspect the record surface to determine whether further cuts on the record, of either a heavy or finishing char- 75

acter, are required to obtain the degree of surface smoothness desired. It is a feature of my invention to permit such immediate inspection of the record by providing, in a machine of the 5 type here described, simple means for automatically stopping the machine at the completion of each cut made on the record. The means for automatically stopping the machine at the completion of the first or heavy cut—i. e., when 10 the carriage reaches its second terminal position—may now be described.

The automatic stopping of the machine, as the carriage is moved into its second terminal position, is effected by an interlinking mechanism between the carriage and the switch 80. This mechanism, as shown in Figs. 1, 2 and 6, comprises an arm 125 pivoted by a pin 126 on an extension 127 projecting forwardly and downwardly from the hub 24' of the carriage 24. 15 The arm 125 is normally held in a downwardly extending position wherein it partially passes through the opening 45 in the base plate 1, as shown in Fig. 6, by a tension spring 128 connected between an ear 125' of the arm 125 and 20 an ear 129 secured to the carriage, this position of the arm 125 being defined by the contact of a stop 125" on the arm with the hub 24' of the carriage. When the carriage nears its second terminal position the arm 125 contacts a turned-up lug 130 on an arm 131 of a lever 132 and turns the lever in a clockwise direction. The lever 132 is pivoted by a screw 133 to a boss 133' on the underside of the base plate 1, and has a rightwardly extending arm 134 slidably connected to a laterally extending bar 135 by a pin 136 on the arm 134 engaging an elongated slot 137 in the bar. The bar 135 is supported by the base plate 1 in a manner permitting a parallel motion of the bar in forward and rearward directions, the bar being connected to the base plate by left and right links 138 and 139 pivoted to the bar 135 by the respective pins 140 and 141 and to the underside of the base plate 1 by the respective screws 140' and 141'. When the lever 45 132 is turned in a clockwise direction, as by the movement of the carriage into its second terminal position, the bar 135 is moved forwardly and the links 138 and 139 are turned in a counter-clockwise direction. Such turning of the link 50 139 causes the switch 80 to be thrown into "off" position by means of a rightwardly extending arm 142 on the link 139 which is coupled, by a long angular link member 143 extending forwardly along the right side of the machine, to a rightward extension 145 of the plate 89, the link member 139 being pivoted to the arm 142 by a pin 142' and to the extension 145 by a pin 144.

In order that the switch 80 may snap into 60 "off" position, by reason of its toggle nature, as soon as the movement of the carriage into its second terminal position has caused the switch to be moved past dead center position, the link member 143 is loosely connected to the extension 145 by the provision of an elongated slot 146 in the extension through which the pin 144 may slide. When the switch 80 is in "on" position the pin 144 rests in the rearward part of the slot 146; rearward movement of the link member 143 as caused by the movement of the carriage into second terminal position thus causes the plate 89 to be rocked in a counter-clockwise direction to cause the switch to be moved towards "off" position. When the switch 70 75 is moved through dead center position, the

switch snaps into "off" position, causing the pin 144 to take a forward position in the slot 146.

Although the pin 144 normally rests, when the switch 80 is in "on" position, in an inwardly extending notch 146' provided at the rearward end of the slot 146 for reasons hereinafter explained, the pin 144 is automatically moved rightwardly out of this notch into the slot 146 by the movement of the switch 80 through dead center position in the direction of "off" position. The counterclockwise turning of the plate 89 necessary to effect such movement of the switch causes an inclined cam face 147, provided at the end of a principally leftwardly extending portion 143' of the link member 143, to impinge against the boss 87 and thereby to limit the leftward movement of the link member 143 so as to cause the pin 144 to be moved out of the notch 146'. When the switch 80 is past dead center position the pin 144 is out of the notch 146' leaving the switch free to snap into "off" position.

If the machine is to be restarted while the carriage is in its second terminal position it will 25 be for the purpose of taking a finishing cut on the record. The finishing-cut operation is wholly controlled by a finishing-cut controlling lever 149. This lever is arranged so that by a single manipulation thereof all actions are performed which are necessary to place the machine in 30 such operating condition as will cause a finishing cut to be taken. To prevent the operator from inadvertently restarting the machine for the finishing-cut operation by manipulating the control lever 86, this lever is rendered ineffective as a means for restarting the machine while the carriage is in its second terminal position. This is done by the pin 144 remaining in the notch 146' until the switch 80 has been moved past its dead center position in the direction of "off" 35 40 position. In moving the switch 80 in the direction of "on" position, the rearward end of the slot 146 will impinge against the pin 144 before the dead center position of the switch is reached. Such impingement causes the link member 143 45 to be urged forwardly, but a forward movement of the link member is prevented while the carriage 24 is in its second terminal position, thereby preventing the moving of the switch into "on" position as by the lever 86. 50

When, however, the carriage is returned from its second terminal position the arm 125 is moved free of the lug 130 and the link member 143 is then moved forwardly, by a tension spring 148 connected between the link member and a pin 148' on the base plate 1. The most forward position of the link member 143 is defined by the abutment of the bar 135 against a stop lug 139' on the link 139. When the link is in this position and the switch 80 is in "off" position the pin 144 rests in the forward end portion of the slot 146. The switch 80 may then be manipulated into "on" position by the control lever 86. When the switch is moved into "on" position the pin 144 again engages the notch 146' by 60 65 reason of the spring 148 being directed so as to also urge the link member 143 leftwardly.

Upon the inspection of the record surface at the completion of a heavy cut on the record the operator will normally do one of three things: 70 remove the record from the machine, take another heavy cut, or take a light finishing cut.

If a record is to be removed the operator will first open the end gate 10 and then operate a record ejector which, being well known in the art, 75

is sufficiently described in the present instance by the statement that it comprises a leftwardly extending handle 46 integral with a hub 47 and an upstanding arm 48, pivoted on a pin 49 supported by the intermediate standard 3 and a standard 50, positioned in front of the standard 3, to which the pin is made secure by a set screw 51; and a shoe 52 carried by the arm 48 and adapted to contact the record when the record ejector is operated. The ejector is normally maintained in an unoperated position, shown in Fig. 1, by a coil spring 53, but in the operation of the ejector the handle 46 is raised against the force of the spring 53 to move the shoe 52 rightwardly against the record to push the record off from the mandrel 18. Commonly provided in combination with the record ejector is a mandrel brake operated by the ejector and comprising an arm 54 pivoted on the pin 49 behind the ejector arm 48 and bearing a brake shoe 55. The coupling between the ejector and the brake comprises a spring 56 coiled about the hub 47 and hooked at one end about a forwardly extending pin 57 on the arm 54 and at the other end about a rearwardly extending pin 58 on the ejector arm 48 located to the right of the pin 57, the spring 56 thus urging pins 57 and 58 into contact with each other. Thus, when the record ejector is operated the shoe 55 is yieldably moved into contact with the mandrel to retard by friction rotation thereof.

If, at the completion of a heavy cut on the record, the operator decides to take another heavy cut on the record, he will release the tool from its set position by returning the tool-setting lever 38 to its unoperated position, and then return the carriage to start position, the initial returning movement of the carriage causing the control lever 86 to be rendered effective as a means for manipulating the switch 80 into "on" position as hereinbefore described. Upon the returning of the carriage to start position, the resetting of the tool and the moving of the control lever 86 to place the switch 80 into "on" position, the machine will go into operation to take another heavy cut. At the completion of this cut the machine will be again automatically stopped; at this time the above set of operations may be again repeated to effect another heavy cut, if desired.

If, at the completion of a heavy cut—such cut being usually sufficient to remove substantially all of the record material necessary in the resurfacing of the record—the operator decides to take a finishing cut for the purpose of smoothing or polishing the record surface, he will manipulate the heretofore mentioned finishing-cut controlling lever 149 downwardly. This causes the resurfacing tool to be advanced towards the record and the carriage to be fed across the record in a rightward direction from the second terminal position—i. e., returned to its start position—to cause the finishing cut to be taken.

The finishing-cut controlling lever 149 is mounted on the left end of the front carriage supporting rod 22 and is normally maintained in an upward or inoperative position, shown in Fig. 6. As the lever 149 is manipulated into a downward or operative position, shown in Fig. 3, various operations are effected to place the machine in condition for taking the finishing cut. These operations comprise principally the moving of the resurfacing tool a predetermined distance towards the record, the rightward shifting of the clutch collar 75 into engagement with the clutch member 73 to reverse the action of the carriage feeding means, and the throwing of the switch 80 into

"on" position to cause the machine to be put into operation.

The means for causing the resurfacing tool 28 to be moved towards the record, into a position for taking a finishing cut thereon, may be first described. Reference being had to the figures, particularly Figs. 1, 2 and 5, it will be seen that the finishing-cut controlling lever 149 is secured to the left end of the carriage supporting rod 22 by a pin 150 so that the rod 22 will turn coordinately with the lever 149 as this lever is moved between its operative and inoperative positions. The rod 22 is provided with left and right eccentric end portions 151 and 152 of which the leftward end portion 151 appears clearly in the enlarged view 15 of Fig. 5. These left and right end portions are respectively journaled in the left and right standards 4 and 7, the left end portion 151 having an annular groove 153 engaged by a set screw 153' in the standard 4 to restrict the rod 22 against longitudinal movement. When the lever 149 is swung downwardly into its operative position the rod 22 is turned in a counterclockwise direction as viewed from the right end thereof. The eccentric end portions 151 and 152 are so positioned relative to the rod 22 (see Fig. 5) as to cause the rod 22 to move downwardly when the finishing-cut controlling lever 149 is moved into operative position. This downward movement of the rod 22 causes the carriage 24 to be tilted slightly downwardly, thereby causing the resurfacing tool to be moved towards the record. As the lever 149 is returned to inoperative position the reverse action takes place: the rod 22 being turned in a clockwise direction, the carriage being tilted upwardly into normal position, and the tool being retracted from the record.

In order that a movement of the finishing-cut controlling lever 149 into operative position may cause the carriage-feeding means to be reversed the lever 149 is provided with an arm 154 extending downwardly through an elongated opening 155 in the base plate 1. Pivotally connected to the lower end of the arm 154, by a pin 154', is a rearwardly extending bar 156. This bar is slidably supported at its rearward end portion by a shoulder screw 157 which passes through an elongated slot 158 in the bar to thread into a standard 159 extending downwardly from the base plate 1. The bar 156 is coupled to the clutch collar 75 by an L-shaped lever 160 having a vertical leg 160' extending through an opening 161 in the base plate 1 and a horizontal leg 160'' below the base plate 1 which extends rightwardly in normal relation to, and to a position below, the bar 156. The vertical leg 160' is pivoted, as by a shoulder screw 162, to a rearwardly extending boss 162' on an upright standard 163 positioned in front of the clutch collar 75, and carries at its upper end a pin 164 engaging an annular groove 165 in the clutch collar 75. Coiled about the boss 162' is a torsional spring 166, hooked at one end on the standard 163 and at the other end on the leg 160' of the lever 160, for biasing the lever 160 in a counterclockwise direction. This biasing of the lever 160 causes the clutch collar to be normally held in its most leftward position—the position for carriage advance. When the finishing-cut controlling lever is moved downwardly into operative position, however, the bar 156 is moved rearwardly. As the bar 156 is so moved a cam 167, provided along the lower edge thereof, slidably engages the lower leg 160'' of the lever 160 and thereby turns the lever in a clockwise direction to cause the clutch collar 75 to be moved into its most rightward position.

tion—the position for carriage return. When the finishing-cut controlling lever is returned to inoperative position the reverse action takes place: the cam 167 moving free of the lower leg 160'', and the spring 168 then turning the lever 160 to cause the shifting of the clutch collar 75 into its leftward position.

It will be seen that the cam 167 has an inclined face 167' and a relatively long flat face 167''. In the initial movement of the lever 149 from inoperative to operative position the leg 160'' traverses the inclined face 167' to cause the rightward movement of the clutch collar 75, the collar being then held in position as the leg 160'' traverses the flat face 167''. This is done in order that the carriage feeding means will be reversed before being put into operation, which operation is effected by the final movement of the control lever 149 into operative position, as is now described.

As hereinbefore described, when the carriage 24 is in its second terminal position the switch 80 is locked in "off" position. The initial movement of the finishing-cut controlling lever 149, however, removes the lock on the switch 80, the remaining movement of the lever 149 into operative position then causing the switch 80 to be thrown into "on" position. To remove the lock on the switch 80 the arm 125 is moved rearwardly into a position free of the lug 130, thereby rendering the lever 132 free to turn in a counterclockwise direction so that the link member 143 may move forwardly, as by reason of the spring 148, to place the pin 144 in the forward portion 35 of the slot 146. To move the arm 125 rearwardly there is provided on the bar 156 centrally thereof an arm 168 extending upwardly through the opening 45 in the base plate 1 and turned over to the right to form a horizontal table 169 extending rearwardly from the arm 168 at a level slightly 40 above the lug 130 of the lever 132 and the top of the base plate 1. When the carriage is in its second terminal position and the finishing-cut controlling lever 149 is in inoperative position the rear edge 169' of the table 169 lies directly 45 in front of the arm 125. When the finishing-cut controlling lever 149 is moved through the initial portion of its travel into operative position the table 169 is moved rearwardly over the lug 130, thereby causing the arm 125 to be moved rearwardly out of contact with the lug. When this 50 occurs the lever 132 moves in a counterclockwise direction into the position shown in Fig. 2 to cause the switch 80 to be unlocked.

The means, operated by the lever 149, for throwing the switch 80 into "on" position as shown in Figure 2 and comprises a forward extension 170 on the plate 89, lying below the control lever 86, which is pivotally connected by a pin 170' to a link member 171 which is extended leftwardly and pivotally connected by a pin 171' to an arm 172 of an angular lever 173 pivoted by a pivot screw 174 to a boss 174' extending downwardly from the base plate 1. The other arm 60 172' of the lever 173 carries a pawl 175 pivoted thereto by a pin 176. The pawl 175 is biased in a clockwise direction by a tension spring 176 connected between ears 175' and 173' on the pawl 175 and lever 173 respectively. Movement 65 of the pawl in a clockwise direction is restricted, however, by the contact of a lug 175'' on the pawl with the arm 172'.

When the switch 80 is in "off" position the pawl 175 lies in a position, as shown in dash-dot lines in Fig. 2, in the path of movement of a

bracket member 176 secured to the right side of the bar 156. After the arm 125 has been moved free of the lug 130, in the movement of the finishing-cut controlling lever 149 to operative position, the bracket member 176 contacts the pawl 175 and turns the lever 173 in a clockwise direction; such movement of the lever 173 causes the switch 80 to be moved from "off" position through its dead center position, the switch then snapping into "on" position. When the finishing-cut controlling lever 149 has reached its operative position the bracket member 176 is in the position indicated in dash-dot lines in Fig. 2, the pawl 175 having now been moved out of the path of the bracket 176 in the position shown 15 by reason of the snapping of the switch into "on" position.

The finishing-cut controlling lever 149 is normally maintained in inoperative position by means of a tension spring 177 which urges the 20 bar 156 forwardly, the spring 177 being connected between a pin 178 on the bar 156 and a pin 178' on the base plate 1. When, however, the finishing-cut controlling lever 149 is moved into operative position it is releasably held therein 25 by means of a latch 179 (see Figure 6) carried by the carriage 24 and disposed above the carriage supporting rod 22 in a vertical slot 180 which is provided in the forward portion of the carriage centrally thereof. The latch 179 is pivoted by a pin 181 to a slotted boss 182 extending forwardly of the carriage, and is provided with an arm 183 extending upwardly in front of the carriage and biased thereagainst by a cantilever spring 184 secured to the carriage by a screw 184'. 30 In the slot 180 there is provided a flat disk-like member 185 embracing the rod 22 and splined thereto by means of a key portion 185' on the member 185 engaging a longitudinal groove 186 in the rod 22 as shown in Figure 3. Thus the 35 member 185 moves with the carriage and turns with the rod 22. When the finishing-cut controlling lever 149 is moved into operative position the latch 179 catches on a tooth 185'' provided on the member 185 and locks the rod 22 against 40 turning in a clockwise direction, as viewed from the right end thereof, thereby holding the lever 149 in operative position.

When the finishing-cut operation is started the carriage is fed in a rightwardly direction to its 50 start position. When the arm 125 on the carriage has returned to the right of the lug 130, the arm 125 slides off from the table 169 and moves forwardly, as by reason of the spring 128, into position to contact the lug 130 upon the 55 next advance of the carriage. When the carriage reaches its start position the machine is again automatically stopped, the knife is released, and the finishing-cut controlling lever 149 is returned to inoperative position. Thus there will 60 be next taken a heavy cut upon resetting the tool and restarting the machine.

The means for stopping the machine at the completion of a finishing cut is shown in Figs. 1, 2, 3 and 4, and comprises a lever 187 pivoted by 65 a pivot screw 188 on a leftward extension 7'' of the standard 7. The lever 187 extends downwardly through an opening 189 in the base plate 1 and terminates in a socket 190 fitting over the top of a pin 191 provided on the arm 90 of the 70 plate 89. The upward portion of the lever 187 has a leftwardly extending arm 192 terminating along a vertical face 192', as shown in Fig. 4. Above and to the left of the face 192' there is provided on the lever 187 a cam extension 193. 75

As the carriage nears its start position a short rearwardly extending arm 194 on the member 185 contacts the face 192' and turns the lever 187 in a clockwise direction, as viewed from the front, 5 thereby causing the plate 89 to be turned to cause the switch 80 to be moved towards "off" position. When the switch has been moved, by the return of the carriage, through its dead center position the switch snaps into its "off" position, 10 such snapping of the switch, causing the lever 187 to be turned further in a clockwise direction. As the lever is so turned the cam extension 193 contacts a projection 179' on the latch 179 and moves the latch upwardly out of contact with the tooth 185', thereby releasing the finishing-cut 15 controlling lever 149 from its latched condition. Thus as the carriage moves into start position the switch 80 is moved through its dead center position in the direction from "on" to "off" position; the switch then moves on into "off" position, by reason of its toggle nature, and by such onward movement causes the finishing-cut controlling lever 149 to be returned to inoperative 20 position.

25 When the return of the carriage has caused the switch 80 to be moved past dead center position in the direction of "off" position the pawl 175 is again in the path of the bracket member 176. The subsequent release of the finishing-cut controlling lever 149 causes the bracket member 176 to move forwardly. As the bracket member 176 so moves it first impinges against the pawl 175 and moves the pawl out of its path, as by turning the pawl in a counterclockwise direction 30 against the force of the spring 176. When the bracket has moved past the pawl, the latter then snaps back into the path of the bracket member 176 into the position shown in dash-dot lines in Fig. 2.

40 The means for automatically releasing the resurfacing tool 28 from operative position as the carriage moves into start position comprises, in addition to structure hereinbefore described, an angular lever 195 (see Figs. 1, 6 and 8) pivoted 45 on the carriage, at the right side thereof, by means of a relatively long shoulder screw 196 located below the carriage extension 27. This angular lever comprises a vertically extending lower portion 197 disposed in front of the bar 135 for sliding contact therewith; a central substantially semi-circular portion 198 partially surrounding the hub 24' of the carriage rearwardly thereof, and pivoted at its upper end on the shoulder screw 196 adjacent to the right side of 50 the carriage; a bail portion 199 extending rightwardly beneath the screw 196; and a forwardly extending arm 200 pivoted on the outer end of the screw 196 and contacting the underside of the short arm 40 of the tool-setting lever 38 whenever the tool is set in operative position.

Upon moving the switch 80 into "off" position, as for example by the return of the carriage into start position, the plate 89 is turned in a counterclockwise direction. As this occurs the link 65 member 143 is moved rearwardly, as by reason of the pin 144 being engaged with the notch 146', and the bar 135 is thereby moved forwardly. The bar 135, as it is so moved, contacts the portion 197 of the lever 196 and moves it forwardly, 70 thereby causing an upward movement of the arm 200. This upward movement of the arm 200 imparts a clockwise or upward "tripping" movement to the tool-setting lever 38, as by its contact with the arm 40 of the lever 38, to effect the release of the tool from operative position.

After the tool is released the pin 144 is moved out of the notch 146' by the snapping of the switch 80 into "off" position as hereinbefore described; when this occurs the bar 135 is moved rearwardly by the spring 148 out of contact with the lever 196, thereby permitting a resetting of the tool as desired.

It will be recalled that the bar 135 is moved forwardly as an incident of stopping the machine, as by the movement of the carriage 24 into its second terminal position. In order that the tool will not be then released from operative position, to permit a finishing cut to be next taken on the record, the left end portion 135' of the bar 135 is offset to the rear so that the bar 135 will not, in its forward travel, contact the lower portion 197 of the lever 196 while the carriage is in its second terminal position.

Although the movement of the carriage into start position causes the switch 80 to be thrown 20 into "off" position, it will be seen that the control lever 86 is yet operable to throw the switch 80 into "on" position, to restart the machine as for taking a heavy cut on the record, while the carriage is yet in start position. As hereinbefore 25 explained when the switch 80 is thrown into "off" position by the movement of the carriage into start position the cam extension 193 on the lever 187 contacts the latch 179 and releases the finishing-cut controlling lever 149 from operative position. Upon the release of the lever 149, it is moved into inoperative position by the spring 177; this causes the arm 194 of the member 185 to be swung downwardly out of the path of the arm 192 of the lever 187, thereby leaving the 30 switch freely manipulable into "on" and "off" position by the control lever 86.

To prevent possible mis-operation of the machine the finishing-cut controlling lever 149 is rendered ineffective as a means of restarting the machine while the carriage is in start position. It will be seen that upon the initial movement of the finishing-cut controlling lever 149 into operative position the arm 194 is moved up into the path of the arm 192. A further movement of 40 the lever 149 towards its operative position causes the bracket member 176 to contact the pawl 175 and move the switch 80 towards "on" position; however, before the switch is moved past its dead center position the arm 192 impinges against the 45 arm 194 to obstruct further movement of the switch towards "on" position, as by means of lever 149.

Reference being had to Figs. 13, 14 and 15 there will be seen a modified form of tool-setting 55 gauge 201. While the gauge 201 is generally similar in shape to the heretofore described gauge 97 (having a foot 202 for contacting the record and a collar 203 embracing the knife bar 30) it is distinguished therefrom in that the gauge is 60 not movable longitudinally of the knife bar 30 but is secured to the stop collar 37, as by welding the collar 203 thereto. When the gauge 201 is in normal position relative to the resurfacing tool 28 it is positioned to the left of the latter. In 65 moving the lever 38 to set the tool, the foot 202 is first brought into contact with the record surface for positioning the tool relatively thereto, as for a heavy cut on the record; the tool-locking means is rendered operative by the means hereinbefore described; and then the arm 116, carried by the lever 38, contacts the pin 117 of the stop collar 37 and turns the collar in a counterclockwise direction, as viewed from the top. Such turning of the collar 37 causes the foot 202 to 70 75

swing forwardly out of contact with the record into a retracted position as indicated in dash-dot lines in Fig. 15. Upon the release of the tool from operation position the other arm 118, 5 carried by the lever 38, contacts the pin 117 of the stop collar 37 and turns the collar back into its former position, thereby restoring the tool-setting gauge 201 into normal position relative to the tool.

10 Although I have shown and described my invention in certain preferred embodiments, it will be understood that many modifications and changes may be made therein without departing from the scope of my invention, which I undertake to express according to the following claims:

I claim:

1. In a phonograph record resurfacing machine adapted for taking cuts from a record and having a record-supporting means: the combination of 20 a support member; a resurfacing tool slidably mounted on said support member for movement across the record; and manually operable means for changing the level of said support member relative to said record supporting means to cause 25 said tool to be moved towards and away from the record, at will.

2. In a phonograph record resurfacing machine adapted for taking cuts from a record: the combination of a frame; a pair of support rods carried by said frame, one of said support rods having eccentric ends journaled in said frame; a resurfacing tool slidably mounted on said support rods for movement across the record; and means for turning said one support rod to effect movement of said tool towards and away from the record.

3. In a phonograph record resurfacing machine adapted for taking cuts from a record and having a carriage movable across the record: the combination of a resurfacing tool movably mounted 40 on said carriage for movement into and out of operative position relative to the record; driving means for moving said carriage across the record; means for coupling said carriage with said driving means, having operative and inoperative positions; and means, operatively connecting said tool with said coupling means, for causing said coupling means to be maintained in inoperative position when said tool is in inoperative position.

50 4. In a phonograph record resurfacing machine having means for supporting a record: the combination of a carriage movable across the record; a resurfacing tool on said carriage movable into operative and inoperative positions relative to the 55 record; tool-moving means; driving means, connectable with said carriage, for moving said carriage across the record; and means, operated by said tool-moving means, for respectively causing said carriage to be connected with and disconnected from driving means when said tool is in operative and inoperative positions.

5. In a phonograph record resurfacing machine having means for supporting a record: the combination of a carriage movable across the record; 65 a resurfacing tool on said carriage movable into operative and inoperative positions relative to the record; tool-moving means; carriage-driving means comprising a feed screw; a feed nut movably mounted on said carriage for movement into 70 and out of engagement with said feed screw; and means, controlled by said tool-moving means, for effecting engagement and disengagement of said feed nut with said feed screw.

6. In a phonograph record resurfacing machine 75 having means for supporting a record: the com-

bination of a carriage movable across the record; a resurfacing tool on said carriage movable into operative and inoperative position relative to the record; carriage-driving means; coupling means carried by said carriage and movable relative 5 thereto to effect connection and disconnection of said carriage with said driving means; and means, operatively connecting said resurfacing tool with said coupling means, for controlling said coupling means in accordance with the position of said 10 tool.

7. In a phonograph record resurfacing machine having means for supporting a record: the combination of a resurfacing tool; a carriage for said tool movable across a supported record; driving 15 means for reciprocating said carriage to cause said tool to traverse the supported record in alternate directions; means operable to start said driving means at will; and means, operated by said carriage, for stopping said driving means at the 20 completion of each tool-record traversal.

8. In a phonograph record resurfacing machine having a rotatable support for a record: the combination of a resurfacing tool; driving means for rotating said support and for reciprocating said 25 resurfacing tool across the record to cause said tool to traverse the record in alternate directions; a manually throwable switch for starting and stopping said driving means at will; and means, 30 automatically operated incidental to the completion of each tool-record traversal, for throwing said switch to cause stopping of said driving means.

9. In a phonograph record resurfacing machine 35 having means for supporting a record; the combination of a carriage capable of advance and return movements relative to a supported record; a settable record-engaging tool mounted on said carriage, a finishing-cut controlling means; driving means reversible to effect advance and return 40 movements of said carriage; and means, controlled by said finishing-cut controlling means, for reversing said driving means.

10. In a phonograph record resurfacing machine having means for supporting a record: the 45 combination of a carriage capable of advance and return movements relative to a supported record; a settable record-engaging tool mounted on said carriage; a finishing-cut controlling means operable to move said tool a predetermined distance 50 towards the record carriage - moving means; means for automatically stopping said carriage-moving means at the completion of carriage advance; and means, controlled by said finishing-cut controlling means, for restarting said carriage-moving means and reversing the same to cause the carriage return.

11. In a phonograph record resurfacing machine having means for supporting a record: the combination of a carriage; a settable record-engaging tool mounted on said carriage; means for reciprocating said carriage between first and second terminal positions to cause said tool to traverse the record in alternate directions; means for automatically stopping said reciprocating means at the completion of each tool-record traversal; manipulatable control means for starting and stopping said reciprocating means; and means, rendered operative when said carriage is in one of its terminal positions, for rendering 70 said manipulatable means ineffective to control said reciprocating means.

12. In a phonograph record resurfacing machine having means for supporting a record: the combination of a carriage; a settable record- 75

engaging tool mounted on said carriage; means for reciprocating said carriage between two terminal positions to cause alternating traversals of said tool relative to a supported record; means for automatically stopping said reciprocating means at the completion of each tool-record traversal; and control means, operable at will except when said carriage is in a predetermined one of its terminal positions, for starting said reciprocating means.

13. In a phonograph record resurfacing machine having a record support: the combination of a carriage capable of advance and return movements across said support; driving means for said carriage; first and second control means for said driving means respectively operable to cause advance and return movements of said carriage; and means for causing said first and second control means to be respectively inoperative when said carriage is in predetermined positions of its path.

14. In a phonograph record resurfacing machine having means for supporting a record: the combination of a carriage; a settable record-engaging tool mounted on said carriage; a finishing-cut controlling means operable to move said tool a predetermined distance towards the record; means operable to move said carriage between two terminal positions to cause said tool to traverse the record in alternate directions; control means for placing said carriage-moving means in operation to cause said tool to traverse the record in one of said alternate directions; and means, controlled by said finishing-cut controlling means, for placing said carriage-moving means in operation to cause said tool to traverse the record in the other of said alternate directions.

15. In a phonograph record resurfacing machine adapted for taking cuts from a record: the combination of a carriage movable between two terminal positions; a settable record-engaging tool mounted on said carriage; a finishing-cut controlling means normally operable to move said tool a predetermined distance towards the record; and means for automatically rendering said finishing-cut controlling means inoperative when said carriage is in a predetermined one of its terminal positions.

16. In a phonograph record resurfacing machine adapted for taking cuts from a record: the combination of a carriage; a finishing-cut controlling means movable into operative and inoperative positions; a carriage-feeding means; and means, operated incidental to the movement of said finishing-cut controlling means into operative position, for placing said carriage-feeding means in operation to cause said carriage to be moved across the record.

17. In a phonograph record resurfacing machine adapted for taking cuts from a record: the combination of a resurfacing tool; a finishing-cut controlling means movable into operative and inoperative positions; means operable to move said tool back and forth across the record; means for starting said tool-moving means as an incident of moving said finishing-cut controlling means into operative position; and means, operated incidental to the completion of a traversal of the record by said tool, for returning said finishing-cut controlling means to inoperative position and for stopping said tool-moving means.

18. In a phonograph record resurfacing machine having a rotatable support for a record:

the combination of a tool-carriage; driving means selectively operable to advance and to return said carriage relative to a supported record; control means for said driving means movable into start and stop positions; means for automatically moving said control means into stop position at the completion of carriage advance; means for moving said control means into start position and for simultaneously reversing said driving means to cause the return of said carriage; and means, automatically operated at the completion of carriage return, for moving said control means into stop position and for rendering said driving means operable to advance said carriage.

19. In a machine adapted for resurfacing phonograph records: the combination of a tool-carriage; means for reciprocating said tool-carriage across a record to be resurfaced; a manually operable control switch having start and stop positions for rendering said reciprocating means operative and inoperative; means, operated by the movement of said tool-carriage into one end of its travel, for moving said control switch into stop position; and means, operated incidental to the movement of said control switch into stop position, for rendering said control switch free from said tool-carriage to permit the manual movement of said control switch into start position while said tool-carriage is in said end of its travel.

20. In a machine adapted for resurfacing phonograph records: the combination of a tool-carriage; means for reciprocating said tool-carriage across a record to be resurfaced; a control switch having start and stop positions for rendering said reciprocating means operative and inoperative; means for automatically moving said control switch into stop position as said tool-carriage is moved into one end of its travel; and means operable to move said control switch into start position while said tool-carriage is in said end of its travel.

21. In a phonograph record resurfacing machine having a support for a record: the combination of a tool-carriage movable along a supported record; driving means connectable with said tool-carriage to move the latter; and a manually operable means for controlling both the starting and stopping of said driving means and the connection of the same with said tool-carriage.

22. In a phonograph record resurfacing machine having a support for a record: the combination of a tool-carriage movable along a supported record; driving means connectable with said tool-carriage to move the latter; means operable to effect the connection of said driving means with said tool-carriage; control means for starting and stopping said driving means; and means, controlled by said control means, for disconnecting said tool-carriage from said driving means upon the stopping of the latter.

23. In a machine adapted for resurfacing phonograph records: the combination of a movable resurfacing tool; a gauge associated with said tool and movable into contact with a record to be resurfaced to determine the operative position of said tool relative to the record, said gauge and tool being arranged for relative longitudinal movement; tool-locking means; and means operable by a single manipulation thereof to move said gauge into contact with the record, to render said tool-locking means operative, and to move said gauge out of contact with the record, in the sequence named.

24. In a machine adapted for resurfacing phonograph records: the combination of a set-table resurfacing tool; a tool-setting gauge normally bearing a fixed spaced relationship to said tool; tool-locking means movable into operative position; and means operable by a single manipulation to effect, in sequence, a movement of said gauge into contact with the record to position said tool relatively thereto, a movement of said tool-locking means into operative position, and a movement of said gauge out of said fixed spaced relationship to render said gauge free of the record.

25. In a machine adapted for resurfacing phonograph records: the combination of a set-table resurfacing tool; a tool-setting gauge pivotally connected with said tool; tool-locking means movable into operative position; and means operable by a single manipulation to effect, in sequence, a movement of said gauge into contact with the record, a movement of said tool-locking means into operative position, and a pivotal movement of said gauge relative to said tool and out of contact with the record.

26. In a machine adapted for resurfacing phonograph records: the combination of a resurfacing tool lockable into operative position relative to a record to be resurfaced; a gauge normally bearing a fixed relationship to said tool and movable into contact with the record to determine the operative position of said tool; means for causing said gauge to be moved out of said normal fixed relationship to said tool as an incident of locking the latter; and means, operated as an incident of moving said tool out of operative position, for restoring said gauge into normal relationship to said tool.

27. In a machine adapted for resurfacing

phonograph records: the combination of a resurfacing tool movable into and out of operative position relative to a record to be resurfaced; tool-locking means; a tool-setting gauge movable into contact with the record to determine the operative position of said tool relative to the record; means for moving said gauge out of normal position relative to said tool and out of contact with the record as an incident of operating said tool-locking means; and means, operated as an incident of moving said tool out of operative position, for returning said gauge into normal position relative to said tool.

28. In a machine adapted for resurfacing phonograph records: the combination of a set-table resurfacing tool; a tool-setting gauge movable into contact with a record to be resurfaced to position the tool relatively thereto; means for moving said gauge relative to said tool to free the gauge from the record as an incident of tool setting; and means for automatically and temporarily restoring said gauge relative to said tool to render the gauge effective for a resetting of the tool as an incident of such resetting.

29. In a phonograph record resurfacing machine having a record support and a carriage: the combination of a resurfacing tool on said carriage settable into operative position relative to a record on said support; a finishing-cut controlling means operable to advance said tool towards said support; means for reciprocating said carriage along said support; and means, automatically operated at the completion of one reciprocation of the carriage, for returning said tool from set position and said finishing-cut controlling means from operative position and for rendering said reciprocating means inoperative.

GEORGE H. FRITZINGER.

CERTIFICATE OF CORRECTION.

Patent No. 2,209,834.

July 30, 1940.

GEORGE H. FRITZINGER.

It is hereby certified that error appears in the printed specification of the above numbered patent requiring correction as follows: Page 2, second column, line 5, strike out the word "taken"; line 62, after "rod" insert the reference numeral --23--; page 10, first column, line 60, claim 4, after "from" insert --said--; and that the said Letters Patent should be read with this correction therein that the same may conform to the record of the case in the Patent Office.

Signed and sealed this 15th day of October, A. D. 1940.

Henry Van Arsdale,

Acting Commissioner of Patents.
